Primary Examiner — David Muller(74) *Attorney, Agent, or Firm* — Dorsey & Whitney LLP(57) **CLAIM**

The ornamental design for an access device, as shown and described.

DESCRIPTION

FIG. 1 is a perspective view of an access device in an assembled configuration, according to a first embodiment; FIG. 2 is another perspective view of the access device shown in FIG. 1; FIG. 3 is a side elevational view of the access device shown in FIG. 1, the other side elevational view being identical; FIG. 4 is a top plan view of the access device shown in FIG. 1, the bottom plan view being identical;

FIG. 5 is a front elevational view of the access device shown in FIG. 1; and, FIG. 6 is a back elevational view of the access device shown in FIG. 1.

The features shown in broken lines do not form part of the claimed design.
